ANTI-KICKING DEVICE FOR COWS

Otto Vilhard Norenborg, Uppsala, Sweden, assignor to Aktiebolaget Separator, Stockholm, Sweden, a corporation of Sweden

Application February 12, 1954, Serial No. 409,979

Claims priority, application Sweden March 6, 1953

8 Claims. (Cl. 119—96)

The present invention relates to a device for preventing cows from kicking during milking, veterinary treatment, etc.

A device made according to the invention is characterized by a frame, or the like, adapted to be placed in front of the udder and the hind-leg knees, between the pelvic brims and the thigh-joints and across the small of the back of the cow, so that the cow's knees are barred. The device is effective primarily because the frame lies in front of the cow's knees but also because of the pressure exerted by the frame on the parts between the pelvic brims and the thigh-joints.

For a better understanding of the invention, reference may be had to the accompanying drawing illustrating a preferred form of the new device. In the drawing, Fig. 1 is a front view of the device; and Fig. 2 is a side view of the device on a reduced scale, showing it fixed on the cow.

The device consists essentially of a frame having a substantially U-shaped bowl and a tightening means 2 arranged on the bow. The U-shaped bow 1 comprises two parts 3 and 4 which are hinged to one another by means of a bolt 5, or the like, at the connective part 6 of the bow. On one part 3 a stop in the form of a boss 7 is fixed, which is arranged to cooperate with the edge 8 of the other part so that the relative turning movement between the bow parts 3 and 4 is limited. The stops 7 and 8 should be so arranged that the bow shanks 9 and 10 form an angle of 70°—100°, preferably 80°, when the stops engage one another.

The shanks 9 and 10 have on their outer sides, near their ends, a plurality of notches 11 suitably arranged directly opposite each other and forming with a flexible element or chain 12 the tightening means 2 of the frame. The chain 12 is provided at its ends with rings 13 forming looped end portions adapted to receive the frame shanks 9—10 and fit into the notches 11.

In order to prevent loss of the chain, it is preferable to lock it permanently to the U-shaped bow 1. For this purpose one of the shanks 9 is provided with a vertical rod 9a, or the like, connected at its ends to the shank above and below the notches 11 but otherwise spaced from this shank. Thus, the rod 9a prevents the adjacent ring 13 from sliding over the end of the shank 9.

When the frame is used, it is placed with its connective part 6 in front of the udder 14 and with its shanks 9 and 10 in front of the knees 15 of the hind-legs and between the pelvic brims 16 and the thigh-joints 17. Then the rings 13 are inserted into the notches 11 so that the chain 12 is stretched tightly. In so doing, the chain should lie across the small 18 of the cow's back. Due to the location of the frame in front of the cow's knees

2

15, and the pressure it exerts between the pelvic brims 16 and the thigh-joints 17, the cow is effectively prevented from kicking.

The invention is not limited to the specific embodiment described above and shown in the drawing, but may be varied in many ways within the range of the following claims.

I claim:

1. A device for preventing cows from kicking during milking, or the like, which comprises a frame adapted to surround the hind quarters of the animal body and including an upper part arranged to rest across the small of the cow's back, and a U-shaped bow having a lower part arranged to extend in front of the cow's udder and also having rigid shanks connected at their upper ends to said upper part and arranged to rest against both flanks of the cow between the pelvic brims and the thigh-joints in front of the cow's hind-leg knees, whereby said knees are barred.
2. A device according to claim 1, in which said upper part of the frame includes tightening means connected between the ends of the bow.
3. A device according to claim 1, in which said upper part of the frame includes tightening means connected between the ends of the bow, said bow having two rigid parts forming said shanks and hinged to each other between the shanks to permit the ends of the bow to move toward and away from each other.
4. A device according to claim 1, in which said upper part of the frame includes tightening means connected between the ends of the bow, said bow having two rigid parts forming said shanks and hinged to each other between the shanks to permit the ends of the bow to move toward and away from each other, and interengageable stops on the bow for limiting said movement of the ends of the bow.
5. A device according to claim 1, in which the frame includes a flexible element forming said upper part.
6. A device according to claim 1, in which the frame includes a flexible element forming said upper part, said shanks being formed with notches, the flexible element having looped end portions through which the shanks extend and fitting into said notches.
7. A device according to claim 1, in which the frame includes a flexible element forming said upper part, said shanks being formed with notches, the flexible element having looped end portions through which the shanks extend and fitting into said notches, and means on one of said shanks for locking the flexible element thereto.
8. A device according to claim 1, in which the frame includes a flexible element forming said upper part, said shanks being formed with notches, the flexible element having looped end portions through which the shanks extend and fitting into said notches, and a rod connected at its ends to one of the shanks above and below the notches therein to lock the flexible element to said last shank.
